UNITED STATES PATENT OFFICE.

MARTIN F. HOWLEY, OF PITTSBURG, PENNSYLVANIA.

CONCRETE GUTTER.

No. 856,702.

Specification of Letters Patent.

Patented June 11, 1907.

Application filed September 17, 1906. Serial No. 334,851.

To all whom it may concern:

Be it known that I, MARTIN F. HOWLEY, a citizen of the United States of America, residing at Pittsburg, in the county of Allegheny and State of Pennsylvania, have invented certain new and useful Improvements in Concrete Gutters, of which the following is a specification, reference being had therein to the accompanying drawing.

10 This invention relates to concrete gutters, and its object is to provide a gutter especially adapted for draining country roads, to prevent damage to the roads by the accumulation of water thereon, and by heavy rains.

15 The invention comprises a concrete structure of suitable form in cross section to provide a drain gutter, adapted to be constructed in lengths or sections and placed end to end in position along the sides of roadways, 20 to form a continuous gutter to carry off drainage and thus protect the road surface.

The invention further consists of a concrete gutter of suitable cross-sectional contour provided with laterally extending flanges 25 or projections adapted to be embedded in the soil alongside a roadway to firmly anchor the gutter and prevent its being loosened or washed away by heavy falls of rain.

30 The construction of the improvement will be fully described hereinafter, in connection with the accompanying drawing which forms a part of this specification, and its novel features will be defined in the appended claims.

35 In the drawing, Figure 1 is a transverse vertical section of a concrete gutter constructed in accordance with the invention and shown as embedded in the soil at the side of a road, Figs. 2 and 3 are similar views showing modified forms of the invention.

40 In Fig. 1 the body or trough portion 1 of the gutter, is of semi-circular form in cross section, and its edges 2 are curved outward and downward to adapt them to be firmly embedded in the earth in such a manner as to prevent their being loosened or washed out 45 by overflow.

The material of which the gutter is constructed may be any of the well known concrete compositions consisting of sand, 50 cement, gravel, etc., and the invention is not restricted to any particular composition.

In Fig. 2 a modification is shown in which the body or trough portion 1^a of the gutter is of V-shape in cross section with its edges 2^b deflected downward at opposite inclinations and embedded in the earth as shown.

In the form of the device shown in Fig. 3 the body or trough portion 1 is of semi-circular form in cross section, and its edges are curved downward and then extend outward 60 in opposite directions to provide horizontal anchoring flanges 4.

In each of the structures shown the body portion and the anchoring flanges are of equal thickness throughout the width of the gutter 65 and the body-portion (that portion within which the drainings are adapted to flow) is free from any surface projections of sufficient magnitude to prevent a free withdrawal of the gutter from its bed when the flange has 70 been freed for such removal. Hence, there is provided a structure which can be readily formed by molding or otherwise, and which is free from weakened points such as would be provided by the placing of flanges, etc., in 75 position to project from the surface of the body-portion intermediate the ends of its side-walls, while the freedom from the surface projections permits of the making of repairs with a minimum amount of labor, there being no requirement of the removal of any earth from any point beneath the body portion proper, while the preparation of the bed and the positioning of the gutter therein requires no special skill nor any tamping below 80 the surface of the gutter. Furthermore, by carrying the flanges below the top plane of the wall of the body-portion, the free edges of the flanges being spaced from said walls, 85 said flanges become anchoring and positioning flanges embedded within the earth; the flanges providing two portions each of which extend downwardly in a direction angular with respect to and lying without the plane of a line drawn vertically through the point 90 of juncture of the flange and the side-wall of the gutter, the structure at the point where the side-walls of the gutter merge into the flanges being such as to provide two portions extending in relatively reverse directions 95 from the top plane of the gutter, the result being to provide each side of the gutter with a laterally extending-portion above which the earth or surrounding material may be placed to resist rising movement of the gutter. 100 In addition, the fact that the point of juncture of the side-wall and the flanges is not an abrupt angle, but is in the form of a relatively extended and reinforced structure, 105 liability of damage thereto is greatly eliminated.

The gutter will be constructed in lengths

or sections fitted together to provide a continuous gutter and the utility and advantage of thus providing drainage for country roads will be apparent.

5. An important characteristic of the invention is the provision of the oppositely projecting continuous anchoring flanges adapted to be so embedded in the earth as to prevent their being easily loosened or washed out by heavy rains.

It is obvious that the invention is not restricted to any particular cross-sectional contour of the gutter but includes all such forms thereof as may fall within the terms and 15 scope of the following claims.

What I claim and desire to secure by Letters Patent, is:—

1. A road drain comprising a concrete gutter, a cross section of which is in the form of a 20 depressed drainage-receiving body-portion terminating in oppositely-disposed positioning and anchoring flanges of equal length with the body portion, the walls of said body-portion and said anchoring flanges extending 25 in relatively reverse directions from the top plane of the gutter, each flange extending in a direction angular with respect to and lying without the plane of a line drawn vertically through the point of juncture of the flange and the side-wall of the gutter, each flange being spaced from the side-walls, 30 said anchoring flanges being continuous throughout the length of the section, and said body-portion and anchoring flanges being of substantially equal thickness throughout the width of the gutter.

2. A road drain comprising a concrete gutter, a cross section of which is in the form of a 35 depressed drainage-receiving body-portion terminating in oppositely-disposed positioning and anchoring flanges of equal length with the body portion, the free edges of said flanges being below the top plane of the gutter.

ter and spaced from the walls thereof, each 40 flange extending in a direction angular with respect to and lying without the plane of a line drawn vertically through the point of juncture of the flange and the side-wall of the gutter, said body-portion and flanges being 45 substantially free from surface projections and of equal thickness throughout the width of the gutter.

3. In an open-top gutter composed of concrete and adapted to form a drain for road-ways, the herein-described gutter-section consisting of a body or trough portion provided with anchoring flanges extending from the side walls of the trough portion and projecting below the top plane of said side wall, 55 each flange extending in a direction angular with respect to and lying without the plane of a line drawn vertically through the point of juncture of the flange and the side-wall of the gutter, the free edges of the anchoring 60 flanges being spaced from said side walls, said anchoring flanges being continuous throughout the length of the section, and said body-portion and anchoring flanges being of substantially equal thickness throughout the 65 width of the gutter and free from surface projections.

4. A concrete gutter adapted for use as a drain for road-ways comprising a concavo-convex body portion, having its edges turned 70 downward and projected horizontally to provide anchoring flanges.

In testimony whereof I affix my signature in the presence of two witnesses.

MARTIN F. HOWLEY.
